US0D1060670S

(12) **United States Design Patent** (10) Patent No.: **US D1,060,670 S**
(45) Date of Patent: ** Feb. 4, 2025

(54) **ENDOSCOPE CANNULA**

(71) Applicant: **DEKA Products Limited Partnership**,
Manchester, NH (US)

(72) Inventors: **Zachary E. Cranfield**, Manchester, NH
(US); **David E. Collins**, Amesbury, MA
(US); **Andrew M. Haggerty**, Lake
Mary, FL (US)

(73) Assignee: **DEKA Products Limited Partnership**,
Manchester, NH (US)

(**) Term: **15 Years**

(21) Appl. No.: **29/722,402**

(22) Filed: **Jan. 29, 2020**

Related U.S. Application Data

(62) Division of application No. 29/669,269, filed on Nov.
7, 2018, now Pat. No. Des. 874,647, which is a
division of application No. 29/559,980, filed on Apr.
1, 2016, now Pat. No. Des. 841,160.

(57) **CLAIM**

The ornamental design for an endoscope cannula as shown and described.

DESCRIPTION

FIG. 1 is a bottom, left side perspective view of the endoscope cannula showing only the endoscope cannula; FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The broken lines depict portions of the endoscope cannula that form no part of the claimed design.

1 Claim, 6 Drawing Sheets
